UNITED STATES PATENT OFFICE.

WILTON AUGUSTUS HALL AND THOMAS AUGUSTUS HALL, OF FERNANDINA,
FLORIDA, ASSIGNORS TO THEMSELVES AND LOUIS G. HIRTH, OF SAME
PLACE.

NON-REFILLABLE BOTTLE.

SPECIFICATION forming part of Letters Patent No. 658,213, dated September 18, 1900.

Application filed October 21, 1899. Serial No. 734,323. No model.

To all whom it may concern:

Be it known that we, WILTON AUGUSTUS HALL and THOMAS AUGUSTUS HALL, of Fernandina, in the county of Nassau and State of Florida, have invented a new and Improved Non-Refillable Bottle, of which the following is a full, clear, and exact description.

This invention relates to a non-refillable bottle of that class in which valves are provided which open outward, permitting the outflow of liquid, but preventing inflow; and the invention is especially characterized by a novel form of valve working with a plunger which serves to open the valve when the bottle is turned downward, but which will not act to open the valve when the bottle is in an upright position, thus preventing the refilling of the bottle.

This specification is the disclosure of several forms of our invention, while the claims define the actual scope thereof.

Reference is to be had to the accompanying drawings, forming a part of this specification, in which similar characters of reference indicate corresponding parts in all the views.

Figure 1 is a vertical section of the invention. Fig. 2 is a top view of the valve. Fig. 3 is a top view of the plunger. Fig. 4 is an enlarged vertical section of the lower end of the plunger, and Fig. 5 is a vertical section illustrating a modified construction of the invention.

The bottle has its neck 6 formed with a contraction 7 at its base, in which is permanently secured a stopper 8, of cork, rubber, or like material. This stopper is centrally orificed longitudinally with the neck, and in this orifice a plunger works, which comprises a hollow stem 9 and a head 10 in the shape of a frustum of a cone, said head being provided with a skeleton-like projection 11, continuing the form of the cone and terminating in a point or apex, as shown. In the bottom of the hollow stem 9 an upwardly-opening valve 12 is arranged, such valve being formed, as shown in Fig. 4, with a bead 14 at its underside, the bead lying in a corresponding groove formed in the stem 9 to insure a more effective contact.

Situated in the lower portion of the neck 6

and let into the stopper 8 is a sleeve 15, in which is arranged an easily-destructible partition 16, disposed horizontally and constructed of thin paper or a like tissue of sufficient strength to withstand the action of the plunger when the bottle is inverted. To this partition 16 is attached a cord or string 17, which is adapted to pass out through the mouth of the bottle, as shown, so that upon drawing upon the cord the partition 16 may be torn from its position and removed with the cord 17 from the neck of the bottle. When the partition 16 is in place, it prevents movement of the plunger; but when the partition is withdrawn the plunger is free to move.

Situated in the neck of the bottle, above the sleeve 15, is a sleeve 18, which extends up near the mouth of the neck and has a contracted lower portion projecting inside of the sleeve 15, between which lower portion of the sleeve 18 and the upper portion of the sleeve 15 is secured a valve 19. This valve is formed of a sheet of rubber or like elastic material provided with an opening in its middle. The valve 19 is preferably so constructed that the rubber will pucker or crease at the middle of the valve and will normally close the opening, so as to stop the neck of the bottle, so that no liquid can pass except when the bottle is turned down, thus causing the plunger to drop and project the skeleton-like extension 11 into the opening in the valve 19, and thus spreading apart the pucker or creased portion thereof and opening a passage for the liquid. The valve 19 is of essentially concavo-convex form, the convex side being uppermost, so that the weight of the liquid on the valve will tend to keep it closed and so that the valve will be in position to render easy the opening of the valve by the action of the plunger. The string 17 is passed through the opening in the valve, which closes snugly around the string, as shown, and when the fractured partition 16 is withdrawn from the neck of the bottle the valve 19 gives to permit the passage of such partition past the valve.

The sleeve 18 is held in place by spring-actuated dogs 20, which are mounted in the outer sides of the sleeve and work in corre-

sponding recesses formed in the interior walls of the neck 6, so that when the sleeve is once in place its withdrawal cannot be effected without fracturing the parts of the bottle.

5 Secured in the sleeve 18 are two hard-rubber blocks 21, forming valve-seats, such blocks being formed with double-conical or hour-glass shaped recesses 22 therein, and in these recesses work ball-valves 23. The ball-valves 23 are held from unnecessary movement in the recesses 22 by means of perforated shield-plates 24, which project downward directly over the valves and are inclined, so as to guide the valves in their movements to and from their seats. The upper shield-plate 24 is fastened in the sleeve 18 directly adjacent to the upper end thereof, while the lower shield-plate is fastened in the upper block 21, as shown. With such an arrangement the bottle is filled and then the plunger is seated on the stopper 8, after which the sleeve 15 is inserted, with the partition 16 in place. Then the sleeve 18, bearing the valve 19 and blocks 21 and ball-valves 23, is inserted, so that the dogs 20 engage with the neck of the bottle to hold the sleeve 18 in place, it being understood that the cord 17 is passed through the valve 19 and through the openings in the blocks 21. Then the outer or removable stopper 25 is driven into the mouth of the bottle. When the contents of the bottle are to be decanted, the removable stopper 25 is withdrawn and the cord 17 is drawn upon, so as to fracture the partition 16 and withdraw the same from the neck of the bottle. Then it will be possible to pour out the contents of the bottle; but it will be seen that it will be impossible to refill the bottle without fracturing the devices within the neck thereof.

40 The modification of our invention shown in Fig. 5 consists simply in the arrangements within the sleeve 18^a, which corresponds with the sleeve 18, before described. This sleeve is constructed the same as the sleeve 18, except that the upper end of the sleeve 18^a is, in form, the frustum of a cone, as shown. Within the sleeve 18^a two diagonal partitions 26 are secured, such partitions taking the place of the parts 21, 23, and 24. (Shown in 45 Fig. 1.) These partitions 26 are formed at opposite sides with openings 27 for the passage of the liquid, and through these openings the cord 17 is also passed. The partitions 26 serve to render circuitous the passage through the neck of the bottle, and thus prevent tampering with the valve 19, which with the partition 16 and parts below the same are similar to those parts previously described.

50 Having thus described our invention, we

claim as new and desire to secure by Letters Patent—

1. A bottle, having a valve therein formed of elastic material with an opening therein, the said material being drawn together at the 65 opening so that the elastic properties of the material will cause the opening normally to be closed, and a plunger mounted adjacent to the valve to reciprocate in a fixed path and having a pointed end capable of moving 70 against the valve to spread apart the walls of the opening in the valve.

2. A bottle, having a valve formed of elastic material with an opening therein, the said material being creased or puckered at the 75 opening so that the elastic properties of the valve will cause the opening normally to be closed, a plunger movable against the valve to open the same, a frangible partition situated between the valve and plunger, and 80 means for fracturing such partition.

3. A bottle, having a valve situated in the neck thereof and formed of a sheet of elastic material with an opening therein, the valve being puckered or creased at the opening so 85 as to cause the opening normally to be closed, a plunger movable against the valve to open the same, a frangible partition situated between the valve and plunger, and a cord attached to the frangible partition and passed 90 through the opening in the valve, by means of which cord the partition may be fractured.

4. A bottle, having a sleeve fitted in the neck thereof, a block secured in the sleeve and having an opening therein to form a 95 valve-seat with an inclined surface leading thereto, a valve working on said seat, and a perforated shield-plate supported above the inclined surface of the block parallel with the surface to guide the movement of the 100 valve along such surface.

5. In a non-refillable bottle, the combination of a valve, a plunger movable toward and from the same to actuate the valve, a frangible partition situated between the 105 plunger and the valve, normally to prevent the engagement of the plunger with the valve, and means for fracturing said partition.

6. In a non-refillable bottle, the combination of a valve, and a plunger movable to the 110 valve to open the same, the plunger being essentially frusto-conical in form and having a skeleton-like projection continuing the form of the cone and terminating in a point or apex to engage the valve.
